UNITED STATES PATENT OFFICE.

STEPHEN PILAROWSKI, OF DETROIT, MICHIGAN, ASSIGNOR TO AMERICAN CAN COMPANY, OF NEW YORK, N. Y., A CORPORATION OF NEW JERSEY.

POURING-SPOUT CAN.

1,154,205.

Specification of Letters Patent. Patented Sept. 21, 1915.

Application filed November 24, 1913. Serial No. 802,662.

To all whom it may concern:

Be it known that I, STEPHEN PILAROWSKI, a citizen of the United States, residing in Detroit, in the county of Wayne and State 5 of Michigan, have invented a new and useful Improvement in Pouring-Spout Cans, of which the following is a specification.

This invention relates to improvements in pouring-spout cans.

10 The main object of the invention is to provide a paper can having a pouring spout in which the spout is composed of a part of a wall of the can and with which is associated a minimum amount of sheet metal 15 to form the spout.

In the drawing forming a part of this specification, Figure 1 is an end view of a can showing my improvements in connection therewith; Fig. 2 is a sectional view 20 taken substantially on the line 2—2 of Fig. 1; Fig. 3 is a detail, broken, end view, similar to Fig. 1, but showing the spout in open position; Fig. 4 is a sectional view taken on the line 4—4 of Fig. 3; and Fig. 5 is a perspective view showing the end of the can 25 with the spout in open position.

In said drawing, the body of the can is designated by the reference 10 and as shown is provided with an end 11, the can being 30 preferably formed of paper or other suitable fibrous material. The end 11 is provided with an integral, substantially sector-shaped portion 12 defined by an arc-shaped cut 13, cut radial edge 14 and scored 35 radial edge 15, said portion 12 being oscillatable about the scored edge 15. Secured to the cut radial edge 14 of the member 12 is a substantially sector-shaped piece of sheet metal 16, the outer edge of which is 40 provided with a flange 17 secured to the radial edge 14 by turned-over tangs 18 (see Fig. 3). The flange 17 is provided with an extension 19 to limit the inward movement of the flap 12 and cause it to lie flush with 45 the rest of the can end when the opening is closed and said piece of sheet metal is provided with a projection 20 on its inner edge adapted to engage with the underside of the end wall of the can to limit the outward 50 movement of the pouring spout as shown most clearly in Fig. 5. A label or sticker 21

is indicated in dotted lines in Fig. 1, which may be placed over the pouring spout while the can is being shipped in order to prevent accidental opening of the spout.

As will be understood, in using the can the user will place his finger nail beneath the extension 19 and pull the spout to its open position and the spout can be closed by merely pressing the same inwardly.

From the preceding description it will be seen that I employ a minimum amount of sheet metal to help form the spout and utilize an integral part of the end wall of the can, thereby providing an exceedingly cheap 65 construction.

I claim:

1. The combination of a can having a paper wall, the latter having an integral portion oscillatable outwardly about one 70 side thereof, and a sheet metal member secured to another side of said portion, said portion of the paper wall and sheet metal member forming a pouring spout when the same are swung outwardly, substantially as 75 specified.

2. A dispensing package of the character described comprising a can having a paper end wall provided with an integral, substantially sector-shaped portion oscillatable 80 outwardly about one radial side thereof and having a substantially sector-shaped sheet metal member secured to the other radial side thereof, said sector-shaped portion and the sheet metal member forming a pouring 85 spout when swung outwardly, substantially as specified.

3. A dispensing package of the character described comprising a can having a paper end wall, said wall having an integral, substantially sector-shaped portion thereof oscillatable outwardly about one radial edge and having a substantially sector-shaped sheet metal member secured to the other radial edge, said sheet metal member having 90 projections near each end of its arcuate edge to limit the inward and outward movements thereof, substantially as specified.

4. A dispensing package comprising a paper end wall, said wall having partly cut 10 out therefrom a substantially sector-shaped portion thereof one side of which is left

integral with the said end wall, and a substantially sector-shaped sheet metal member secured to the free radial edge of the sector-shaped portion by bent portions of the metal within which is clamped the said free edge, the said integral and sheet metal portion and member being adapted to hinge and turn together outward and inward on

the said integral side, and to form a closure and a pouring spout for the said package. ¹⁹

Signed this 19 day of November, 1913,
in the presence of two witnesses.

STEPHEN PILAROWSKI.
